UNITED STATES PATENT OFFICE.

GEORGE GOMER, OF BROOKLYN, NEW YORK.

DESIGN FOR A MATCH-BOX.

SPECIFICATION forming part of Design No. 28,177, dated January 18, 1898.

Application filed December 16, 1897. Serial No. 662,225. Term of patent 7 years.

To all whom it may concern:

Be it known that I, GEORGE GOMER, a citizen of the United States, residing at Brooklyn, in the county of Kings and State of New York, have invented and produced a new and original Design for a Match-Box, of which the following is a specification.

The design consists of a match-safe comprising a base with a flaring rim, an inclined top face, and a center piece connected by a channel or gutter portion with the top face. On said center piece rest legs or supports carrying the safe or receptacle portion.

The design is illustrated in the annexed drawings, in which—

Figure 1 is a side elevation of the match-safe partly broken away. Fig. 2 is a plan view of Fig. 1.

The base of the design is shown comprising a flaring rim 1, from which extends an inclined top face 2. The center piece 3 is connected by a channel or gutter shaped ring or portion 4 with face 2. The center piece is shown at a lower level than the top face or

than the highest portion of said top face. The 25 rim 1 is shown with flutings or corrugations 5 extended part way up said rim. The center piece 3 is shown with corrugations or roughenings 6. On the center piece rest legs or supports 7, carrying the safe or receptacle portion 8, shown with a lateral slit or opening at 9. Said safe has a top opening or rectangular hole at 10, and at the bottom of said hole or depression is an elevation 11.

The design gives a striking and characteristic appearance.

What I claim as new, and desire to secure by Letters Patent, is—

The design for a match-safe as herein shown and described.

In testimony whereof I have hereunto set my hand in the presence of two subscribing witnesses.

GEORGE GOMER.
